United States Patent Office.

GEORGE SELSOR, OF PHILADELPHIA, PENNSYLVANIA.

Letters Patent No. 63,106, dated March 19, 1867.

IMPROVEMENT IN NAIL HAMMERS.

The Schedule referred to in these Letters Patent and making part of the same.

TO ALL WHOM IT MAY CONCERN:

Be it known that I, GEORGE SELSOR, of Philadelphia, Pennsylvania, have invented an Improvement in Hammers; and I do hereby declare the following to be a full, clear, and exact description of the same, reference being had to the accompanying drawing, and to the letters of reference marked thereon.

My invention consists of the combination, substantially as described hereafter, of claws with the "pane" of a hammer-head, so that the latter can be used for performing duties to accomplish which has heretofore required two separate hammers. My invention further consists of a groove formed in the "pane" of the head, beneath the claws, for the reception of a nail, which can be driven to its place without the usual manual adjustment.

In order to enable others skilled in the art to make and use my invention, I will now proceed to describe its construction and operation, reference being had to the accompanying drawing which forms a part of this specification, and in which—

Figure 1 represents a side view of a hammer-head with my improvements.

Figure 2, a plan view.

Figure 3, a longitudinal section; and

Figures 4 and 5, views of the heads of ordinary hammers.

A is the head of my improved hammer, and B the handle, the latter being secured to the former by any of the means heretofore employed for the same purpose. On one end of the head is formed the usual "poll" *a*, and at the opposite end, the "pane" *b*, above which are the claws *c*, there being between the "pane" and the claws a space, *m*, (fig. 1,) sufficiently large to admit the head of an ordinary nail. The heads of common hammers have usually been made either in the manner illustrated in fig. 4, or that shown in fig. 5, the former being an ordinary claw hammer, and the latter a riveting hammer. The two styles are combined in my improved hammer, which, as will be readily seen, can be used either as a carpenter's hammer for driving or drawing nails, and other purposes, or for any of the duties for which a riveting hammer is required. In the upper surface of the "pane" *b*, and below the claws *c*, is cut a groove, *x*, in which can rest a nail, as shown in fig. 3, the head of the nail being in contact with the end of the recess *m*, between the claws and the "pane." In many instances it becomes necessary for a carpenter or other operative to drive a nail at a point where it cannot readily be reached to be adjusted and steadied by one hand while being driven by the hammer in the other hand; in such case the nail may be placed in the groove *x*, as shown, and being maintained in a proper position laterally by the groove, may be elevated with the hammer, and driven at any point within reach of the hammer's head.

I do not desire to confine myself to a "pane" of the form illustrated, as my invention may be applied to hammers having panes of different shape, but I claim as my invention, and desire to secure by Letters Patent—

1. The combination, substantially as described, of the claws *c*, with the "pane" of a hammer for the purpose specified.

2. The groove *x* in the pane, beneath the claws, for the purpose described.

In testimony whereof I have signed my name to this specification in the presence of two subscribing witnesses.

GEORGE SELSOR.

Witnesses.

H. HOWSON,

W.M. HALL WAXLER.
